United States Patent Office.

WILLIAM LEATHE, OF WOBURN, MASSACHUSETTS, ASSIGNOR TO HIMSELF, STOUGHTON B. HOLDEN, AND LUTHER L. HOLDEN.

Letters Patent No. 91,547, dated June 22, 1869.

IMPROVEMENT IN BOOTS AND SHOES.

The Schedule referred to in these Letters Patent and making part of the same.

To all whom it may concern:

Be it known that I, WILLIAM LEATHE, of Woburn, county of Middlesex, and State of Massachusetts, have invented certain Improvements in Boots; and do hereby declare the following to be a full, clear, and exact description thereof, reference being had to the accompanying drawings, in which—

Figure 1 represents a boot embodying my improvements.

The object of my invention is to produce a top for a boot, which shall combine the advantages of elastic gorings, with the convenience of buttons, or lacings.

My improved boot-top is capable of a better and neater fit than those which lace or button entirely, or those which have only the elastic goring.

High-topped boots for ladies are apt to bind the leg at the top, where lacing or buttons only are used, while, if goring alone is employed, there is not a good fit at the ankle.

My combination overcomes these objections.

The construction of boots after my invention is simple, and not particularly expensive.

My improvements are more especially adapted to ladies' boots, but may be applied to goods for gentlemen's wear.

In the drawings—

A is the leg of a boot laced about two-thirds of the way up, that is, from m to m , while the remainder is buttoned with lappel D.

B is an elastic goring, set in one or both sides, as desired. The boot may button or lace all the way, but as shown, a better fit is secured than would be by all buttons, while the convenience is greater by buttoning part way.

The method shown is attractive in form and construction—an essential feature in the manufacture of boots and shoes.

The construction shown admits of the display of variety in taste, both in material and color, and boots of the style described really supply a want not heretofore met.

What I claim as new, and desire to secure by Letters Patent, is—

The device A B D m m , as shown in fig. 1, for the leg of a boot, as herein described.

In testimony whereof, I have signed my name to this specification, in the presence of two subscribing witnesses.

WILLIAM LEATHE.
